UNITED STATES PATENT OFFICE

LUDWIG SPITZSTEIN, OF VIENNA, AUSTRIA, ASSIGNOR TO GEORGE S. POLLITZ, OF NEW YORK, N. Y.

CURLING TONGS PROVIDED WITH HEATABLE IRONS

Application filed August 17, 1927, Serial No. 213,505, and in Austria December 26, 1926.

This invention relates to curling tongs provided with heatable irons.

Curling tongs with heating devices of all kinds have been generally known, but they have—one and all—the inherent disadvantage, that they are operated by using glowing bodies, which are warmed to glow heat outside of the iron and then introduced into same. This method entails very considerable fire hazards and requires the presence of a separate source of heat.

It is a purpose of this invention to create curling tongs, ondulating irons and similar devices, provided with a hollow into which the heating body is introduced. The latter is then ignited by means of a fuse or igniting cap and burns out in the closed chamber without the admission of oxygen, communicating its glowing heat to the irons of the tongs and warming same to the degree required. By employing this method any fire hazard as f. i. the ignition of liquid or gaseous fuels or the catching on fire of the hair to be ondulated or similar dangers are quite excluded.

In order to attain this aim it is possible to heat either one or both irons of the tong (profile irons or pressing irons) by means of heating bodies, which are inserted into the hollow parts of the tongs and burn without the introduction of oxygen or heat of any kind brought to bear in these bodies from outside, the hollow parts being completely closed.

The heating bodies inserted carry igniting caps by the friction of which the former are set afire. When these heating bodies are burnt out there remains a strong skeleton which can completely be withdrawn from the iron together with the products of the combustion. The heating body is composed of oxygen supplying material as saltpetre and fuel, as magnesium, for example a so-called "sparkler", so that after the ignition it is capable to glow and burn slowly in a closed container without the admission of oxygen, communicating its heat to its surroundings.

In Fig. 1 the hollow iron 1 of an ordinary curling tongs is shown, the bore 3 of which nearly reaches the turning point 4. The counter iron is executed in the usual manner

and is—when the tongs are shut—warmed together with the other iron, the two irons, which are turnable round the axis 5, being brought into such an intimate contact by the compression of the handles 6, that the combustion of the heating body inserted warms them both at the same time.

Fig. 2 shows a cross section of the iron 1 with the bore 3 extending as far as point 4.

Fig. 3 shows a specimen of a heating body 7 with igniting cap 8, which may be ignited at any friction surface used for matches. It is supported by a metal skeleton 9, which after combustion may be withdrawn altogether from the iron, thereby cleaning the latter.

Fig. 4 illustrates the cross section of both irons shown in Fig. 1 with the same reference numbers.

Fig. 5 shows the cross section of a curling tong of which both irons are made hollow (refer to Figs. 3 and 6).

Fig. 6 shows an ondulating iron with 3 hollow irons 1 which fit into the cavities of the ondulating iron 2 and which—after the combustion of the 3 glow bodies—heat also the ondulation iron.

I claim:

1. A curling iron of the character described, comprising a pair of pivotally connected jaws and handle members for manipulating the same, one of said jaws being hollow and open at its outer end, and a removable dry solid combustible cartridge adapted to be inserted in the hollow jaw at its open end to project beyond the same, and to be ignited to heat said iron.

2. A curling iron of the character described, comprising a pair of pivotally connected jaws and handle members for manipulating the same, one of said jaws being hollow and open at its outer end, and a removable dry solid combustible cartridge adapted to be inserted in the hollow jaw at its open end to project beyond the same and terminating at its outer end in an ignition cap projecting, when the combustible cartridge is inserted, beyond the outer end of the said jaw whereby said cartridge may be ignited.

3. A curling iron of the character described, comprising a pair of pivotally con-

nected jaws and handle members for manipulating the same, one of said jaws being hollow and open at its outer end, and a removable dry solid combustible cartridge embodying a skeleton support therefor and adapted to be inserted and ignited therein to heat said iron, the residue being removable therefrom through said skeleton support.

4. A curling iron of the character described, comprising a pair of pivotally connected jaws and handle members for manipulating the same, one of said jaws being hollow and open at its outer end, and a removable dry solid cartridge composed of fuel and oxygen-providing material in correct proportions to burn the fuel without external supply of oxygen, said cartridge being adapted to be inserted in the hollow jaw at its open end to project beyond the same and be ignited to heat the said iron.

In testimony whereof I affix my signature.
LUDWIG SPITZSTEIN.
